Specification for Design.

Patented Feb. 21, 1922.

Application filed May 10, 1921. Serial No. 468,421. Term of patent 3½ years.

To all whom it may concern:

Be it known that I, ISIDORE KRANZ, a citizen of Poland, and a resident of the city of New York, borough of Manhattan, in the county and State of New York, United States of America, have invented a new, original, and ornamental Design for a Lighting Fixture, of which the following is a specification, reference being had to the accompanying drawings, in which—

The figure is a perspective view of the new design for a lighting fixture.

I claim:

The ornamental design for a lighting fixture, as shown.
